US00D525229S

(12) **United States Design Patent** (10) **Patent No.:** **US D525,229 S**
Friesen et al. (45) **Date of Patent:** **** Jul. 18, 2006**

(54) **MOBILE PHONE**

(75) Inventors: **Mark Friesen**, Tokyo (JP); **Koichi Kawano**, Kawasaki (JP); **Shinichiro Mori**, Hachioji (JP); **Nobutsugu Fujino**, Yokohama (JP)

(73) Assignee: **Fujitsu Limited**, Kawasaki (JP)

(**) Term: **14 Years**

(21) Appl. No.: **29/223,147**

(22) Filed: **Feb. 10, 2005**

(30) **Foreign Application Priority Data**

Aug. 13, 2004 (JP) 2004-024343

(51) **LOC (8) Cl.** **14-03**

(52) **U.S. Cl.** **D14/138**

(58) **Field of Classification Search** D14/137, D14/138, 147-148, 247-248, 144, 218, 341-347; 379/433.01-433.13, 434; D13/168; D21/517; 455/556.1, 556.2, 566, 575.1, 90.3

See application file for complete search history.
